UNITED STATES PATENT OFFICE.

HARRY A. OTTO, OF PITTSBURGH, PENNSYLVANIA, ASSIGNOR TO JOHN M. HOPWOOD, OF DORMONT, PENNSYLVANIA.

REGULATING FEED WATER FOR BOILERS.

Application filed July 21, 1923. Serial No. 653,034.

The invention described herein relates to improvements in mechanism for controlling the feed of water to boilers and has for its object the provision of means whereby the 5 rate of flow of water will be varied by and in accordance with the change of level of the water in the boiler below and above a pre-determined normal level. The invention is 10 hereinafter more fully described and claimed.

In the accompanying drawings forming a part of this specification, Fig. 1 is a side elevation of a feed water mechanism for boilers embodying the improvement claimed herein; 15 Fig. 2 is a sectional view on a plane indicated by the line II-II, Fig. 1; Fig. 3 is a plan view of the thermostatic mechanism controlling the operation of the feed water mechanism; Fig. 4 is a sectional view on an enlarged scale of the pilot valve mechanism, the 20 plane of section being indicated by the line IV-IV, Fig. 2; Fig. 5 is a transverse section on a plane indicated by the line V-V, Fig. 2; Fig. 6 is a view showing the manner of 25 connecting the thermostatic controller to a boiler; and Fig. 7 illustrates the manner of employing a float for controlling the feed water mechanism.

In the construction shown herein the valve 30 is provided at one end with a nozzle 2 adapted to be connected with a water supply pipe and in its side with a nozzle 3 adapted to be connected with a boiler. This chamber is provided 35 interiorly with a cylindrical lining 4 having ports 5 communicating with a peripheral channel 6 communicating with the outlet port 3, and the shell forming the valve 7 which has one end open, is provided with 40 ports 8 adapted to register with the ports 5 more or less fully dependent on the position of the valve as hereinafter described. The stem 9 of the valve is connected to the rod 10 of the piston 11 in the valve operating cylinder 12.

45 It will be observed that although the valve 7 is subjected to the pressure of water in the feed line at both ends, the water flowing to the right hand end through a port 14, said valve will be shifted to the right in a direction to open ports 5, by means of the unbalancing effect of the relatively large stem 9. Since it is an object of the invention to also shift the valve 7 to the left or in a direction to close the ports 5, by the pressure of water 50 in the feed line, a power cylinder 12 having

its piston 11 connected to the stem 9 is connected as by a port 13 to the feed water line. As hereinafter described, suitable valve mechanism is employed to connect the port 13 with the feed water line, or to permit the 60 escape of water from the cylinder such mechanism being operative by and in accordance with changes of level of water in the boiler. The area of the piston 11 should be made sufficiently greater than the cross sec- 65 tional area of the stem 9 to overcome the frictional resistance to the movements of the piston stem and valve.

Provision is made as hereinafter described for an incremental movement of the valve 70 and such movement proportional to changes in level of the water in the boiler. It is desirable, however, that the quantity of water admitted to the boiler for such incremental movement should vary with the rating at 75 which the boiler is operated. To this end, provision is made for varying the transverse dimensions of the effective areas of the ports 5. This can be conveniently effected by axially rotating the valve 7 by means of a 80 lever 14 having one end secured to the piston rod 10, as shown in Figs. 2 and 5. In order to hold the valve in position, provision is made for clamping the lever to a slotted 85 sector 15 having its ends slidably mounted on rods 16 parallel with the piston rod 10.

The flow of water through the port 13 at the right hand end of the valve operating cylinder 12 is controlled by a valve mechanism indicated at A in Figs. 1 and 2 specifically shown in Fig. 4. As shown in Fig. 4, 90 this valve mechanism consists of a shell provided with chambers 17 and 18 and 19, the chamber 17 being intermediate the chambers 18 and 19. The chamber 18 has its port 20 connected to the feed line of the boiler and the chamber 19 has a port 21 connected to the hot well or other suitable receptacle. The intermediate chamber 17 has a port 13^a adapted 95 when the valve mechanism is in position, to register with the port 13 in the valve operating cylinder 12. The chambers 18 and 19 have ports connected to the chamber 17, the flow of water through said ports being controlled by spring-actuated valves 22 and 23, 100 said springs operating to shift these valves to closed position. Stems 24 and 25 project respectively from the valves 23 and 22 into the chamber 17 and bear at their ends against an arm 26 on a shaft 27. It will be clearly 110

- seen in the construction shown in Fig. 4 that when the arm 26 is shifted downwardly, the valve 22 will be unseated, thereby permitting water under pressure to flow through 5 the port 20, chamber 18, and port leading to the chamber 17 from which it passes through port 13^a into the cylinder 12 and will force the piston to the left or in a direction to check the flow of water through 10 the valve chambers. When the arm 26 is moved upwardly, the valve 22 will be seated and the valve 23 opened, permitting water to flow back through the chambers 17 and 19 through exhaust port 21. Pressure being 15 thus reduced in the valve operating cylinder 12, the pressure of water against the valve 7 will force that valve to the right or in a direction to permit a freer flow of water to the boiler.
- 20 It is preferred that the regulating mechanism should be so adjusted that the arm 26 should be moved to a position permitting the outlet valve 23 to be closed but without opening the inlet valve 22, so that the piston and 25 valve 7 will be held in the position to which they were moved. If, however, the water in the boiler continues to drop, the arm 26 will be moved to again open the outlet port and thereby permit a further incremental movement of the valve 7 and piston 11 to the right, thereby permitting an increase in the flow 30 of water to the boiler. As soon as the water begins to rise in the boiler, the arm 26 will be shifted to open the inlet 22 permitting water 35 under pressure to flow into the cylinder 12 and cause a movement of the piston 11 and valve 7 to the left reducing the flow of water to the boiler. If in such position of the valve 7 the water rises above the desired level, the 40 arm 26 will be again shifted to open the valve 22 and the piston and valve 7 will be shifted to the left to reduce the inflow of water to the boiler.
- On the shaft 27 whereby the valves 22 and 45 23 are shifted, as hereinbefore described, is secured an arm 28 as shown in Fig. 1, and this arm has its end connected by a link 29 to a rod 30 having one end pivotally connected to a sleeve 31, while its opposite end is pivotally connected as at 32 to an arm 33 on a 50 shaft 34. This shaft 34 is also provided with an arm 35 preferably counterweighted and connected by an adjustable link 36 to means operative by and in accordance with changes 55 of the level of water in the boiler. When the arm 36 is permitted to be moved downwardly by the counterweight or otherwise, as the level of water in the boiler rises, the outer end of the arm 33 on the same shaft will be 60 moved upwardly, thereby shifting the rod 30 on its pivotal point and through the medium of the link 29 raising the arm 28 so as to shift the shaft 27 in a direction to move the valve operating arm 26 (see Fig. 4) opening the valve 22, to allow water under pres-
- sure to flow to the right hand end of the operating cylinder 12, as hereinbefore described. By this admission of water to the cylinder 12, the piston 11 and valve 7 are moved to the left. By this movement of the piston a bar 70 37 adjustably connected to the end of an arm 38 secured to the piston rod 10 is moved to the left through the shoe 31, connected as before stated, to the rod 30. As this bar 37 is arranged at an angle to the axis of the piston rod, the shoe and the left hand end of the rod 30 will be moved downwardly, as in Fig. 1, the rod 30 turning on the pivotal point 32 and by reason of its connection through the link 29 to the arm 28, the latter will be moved 75 down or in a direction to permit of the closing of the valve 22 by its spring, thereby stopping a further flow of water to the right hand end of the cylinder 12. It will be readily understood that by shifting the angular position of the bar 37 with reference to the axis of the piston 11 and valve 7, the range of movement of the piston before the valves 22 and 23 are shifted, can be increased or diminished as desired. The angular position 80 of the bar 37 may be shifted by any desired adjustment mechanism, such, for example, as an adjusting screw 51 threaded through a lug 52 on the bar and is rotatably supported in a bracket arm 53 mounted on the arm 38. 85 Collars 54 are secured to the adjusting screw on each side of the arm.
- In Figs. 1 and 3 is shown a form of thermostatic device for operating the compensating valve operating mechanism hereinbefore described. This device consists of a metal tube 39 having one end pivotally connected to a bracket 40, while its opposite end is secured in a block 41. The latter is also connected preferably by two rods 42 to the bracket 40 105 at a point above the connection of the tube 39 therewith, said rod or rods being pivotally connected to the bracket and block. The lower end of this tube is connected by a pipe 43 to the boiler at a point below the water 110 level therein, while the upper end of the tube is connected by a pipe 44 to the boiler at a point above the normal water level, so that the lower portion of this tube will contain 115 water which has had its temperature lowered by radiation to a temperature somewhat lower than that in the boiler, while the upper part will be filled with steam and partake of the temperature thereof. As the water level in the boiler drops, the water in 120 the tube will drop down, exposing a further length of the tube to the higher temperature of the steam, causing an expansion of the tube, such expansion operating to raise the righthand end of the device. As water rises 125 in the tube, the proportion subjected to steam temperature will be reduced and the tube will correspondingly contract and its right hand end drop.
- In lieu of employing this thermostatic de- 130

vice, the link 36 may be connected to an arm 46 projecting from the boiler and secured to the shaft also having an arm 47 carrying a float 50.

5 I claim herein as my invention:

1. A mechanism for controlling the feed of water to a boiler having in combination a valve controlling the flow of water to the boiler, a motor for shifting said valve and operative by the pressure of water in the feed line of the boiler, a valve for regulating the flow of feed water to the motor, means operative by and in accordance with changes of level of water in a boiler for shifting said motor regulating valve in one direction and means operative by the movement of the motor for reversing the movement of the motor regulating valve.

2. A mechanism for controlling the feed of water to a boiler having in combination a valve for regulating the flow of water to the boiler, a cylinder connected to the feed line and having a piston connected to the feed water valve, a valve mechanism, mechanism for shifting said valve mechanism to vary the pressure exerted by the feed water on the piston and operative by and in accordance with changes of level of water in the boiler, and mechanism operative by the piston 30 for shifting the said valve mechanism to closed position after any predetermined movement of the piston.

3. Apparatus for controlling the flow of feed water to a boiler, comprising a feed 35 water line communicating with the boiler, a valve in said line for controlling the flow of feed water therethrough, a pressure actuated motor for controlling the operation of said valve, a mechanism movable in opposite directions from a neutral position for controlling the delivery of operating fluid to or from said motor, means responsive in operation to variations in the water level within the boiler for actuating said mechanism to admit actuating fluid to or discharge actuating fluid from said motor, and means actuated by the movements of said motor for moving said mechanism to the neutral position on each movement of said motor.

50 4. Apparatus for controlling the flow of feed water to a boiler, comprising a feed water line communicating with the boiler, a valve in said line for controlling the flow of water therethrough, a pressure actuated motor for actuating said valve, a mechanism movable in two directions from a neutral position to deliver actuating fluid to or from said motor, means responsive in operation to variations in the water level within the boiler 55 for moving said mechanism in one direction or the other from the neutral position, and means actuated by movements of said motor for moving said mechanism back to the neutral position to cut off the flow of actuating fluid to or from said motor.

5. Apparatus for controlling the delivery of feed water to a boiler, comprising a feed water line communicating with the boiler, a valve located in said line for controlling the delivery of water to the boiler, a motor for 70 actuating said valve, a mechanism movable in opposite directions from a neutral position for controlling the operation and the direction of movement of said motor, means responsive in operation to variations in the 75 water level in said boiler, for moving said mechanism in one or the other direction from the neutral position, and adjustable means actuated by movement of said motor for returning said mechanism to its neutral position. 80

6. Apparatus for controlling the delivery of feed water to a boiler, comprising a feed water line communicating with the boiler, a valve located in said line for controlling the 85 flow of water to the boiler, a motor for actuating said valve, a mechanism movable in opposite directions from a neutral position for controlling the operation and the direction of movement of said motor, means responsive in operation to variations in the 90 water level within said boiler, for moving said mechanism in one or the other direction from the neutral position, adjustable means actuated by movement of said motor for returning said mechanism to the neutral position, and adjustable means for varying the effective opening of said valve independently of the extent of movement of said motor. 95

7. An apparatus for controlling the delivery of feed water to a boiler, comprising a feed water line communicating with the boiler, a valve located in said line for controlling the delivery of water to the boiler, a fluid pressure motor for actuating said valve, a 100 mechanism movable in opposite directions from a neutral position for controlling the delivery of actuating fluid to and from said motor, means responsive in operation to variations in water level within the boiler for 105 moving said mechanism in one direction or the other to admit or discharge actuating fluid from said motor, an inclined way movable by said motor, a shoe mounted thereon and slidably therealong and a system of instrumentalities operatively connected to said shoe and movable thereby to return said mechanism to the neutral position on a determined movement of said motor. 110

8. An apparatus for controlling the delivery of feed water to a boiler, comprising a feed water line communicating with the boiler, a valve located in said line for controlling the delivery of water to the boiler, a pressure actuated motor for moving said 115 valve, a mechanism movable in opposite directions from a neutral position for controlling the delivery of actuating pressure to and from said motor, means responsive in operation to variations in water level in the boiler 120

125

130

for moving said mechanism in one direction or the other, a way adjustable to different inclinations and moving with said motor, a shoe slidably mounted on said way, and instrumentalities operatively connected to said shoe and movable thereby to return said mechanism to the neutral position on movement of said motor.

9. Apparatus for controlling the delivery 10 of feed water to a boiler comprising a feed water line communicating with the boiler, a control valve located therein and movable in one direction by the pressure of the feed water thereon, a water motor for moving said 15 valve in the other direction, a valve mecha-

nism for controlling the delivery of feed water to and from said motor and including an instrumentality movable in opposite directions from a neutral position to actuate said valve mechanism, means responsive in operation to variations in water level within the boiler for moving said instrumentality in one direction or the other, and means operatively connected to said instrumentality and movable by said motor for returning said instrumentality to the neutral position on a determined movement of said motor.

In testimony whereof I have hereunto set my hand.

HARRY A. OTTO.
